US00D967732S

(12) **United States Design Patent** (10) **Patent No.:** **US D967,732 S**
(45) **Date of Patent:** **** Oct. 25, 2022**

(54) **VEHICLE BODY**

(71) Applicant: **National Association for Stock Car Auto Racing, LLC**, Daytona Beach, FL (US)

(72) Inventors: **Brandon Thomas**, Concord, NC (US); **John Probst**, Concord, NC (US); **Eric Jacuzzi**, Concord, NC (US); **Christopher A. Popiela**, Concord, NC (US); **Timothy S. Murphy**, Concord, NC (US); **Donald E. Krueger**, Concord, NC (US)

(73) Assignee: **NATIONAL ASSOCIATION FOR STOCK CAR AUTO RACING, LLC**, Daytona Beach, FL (US)

(**) Term: **15 Years**

(21) Appl. No.: **29/753,868**

(22) Filed: **Oct. 2, 2020**

(51) LOC (13) Cl. **12-08**

(52) U.S. Cl. **D12/92**
USPC ....

Primary Examiner — Melody N Brown

(74) Attorney, Agent, or Firm — Alston & Bird LLP

(57) **CLAIM**

The ornamental design for a vehicle body, as shown and described.

DESCRIPTION

FIG. 1 is a top, front and left side perspective view of a vehicle body showing our new design;

FIG. 2 is a top, rear and right side perspective view thereof;

FIG. 3 is a top plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken lines shown throughout the drawing views are for illustrative and environmental purposes, and represent some boundaries that form no part of the claimed design.

1 Claim, 6 Drawing Sheets
